(57) **CLAIM**

The ornamental design for a barbecue grill, as shown and described.

DESCRIPTION

FIG. 1 is a front perspective view of a barbecue grill, in accordance with the invention;

FIG. 2 is a front view of the barbecue grill shown in FIG. 1;
FIG. 3 is a rear view of the barbecue grill shown in FIG. 1;
FIG. 4 is a left side view of the barbecue grill shown in FIG. 1;

FIG. 5 is a right side view of the barbecue grill shown in FIG. 1;

FIG. 6 is a top view of the barbecue grill shown in FIG. 1;
FIG. 7 is a bottom view of the barbecue grill shown in FIG. 1;
FIG. 8 is a front perspective view of a first storage configuration of the barbecue grill shown in FIG. 1;

FIG. 9 is a front view of the first storage configuration of the barbecue grill shown in FIG. 1;

FIG. 10 is a rear view of the first storage configuration of the barbecue grill shown in FIG. 1;

FIG. 11 is a left side view of the first storage configuration of the barbecue grill shown in FIG. 1;

FIG. 12 is a right side view of the first storage configuration of the barbecue grill shown in FIG. 1;

FIG. 13 is a top view of the first storage configuration of the barbecue grill shown in FIG. 1;

FIG. 14 is a bottom view of the first storage configuration of the barbecue grill shown in FIG. 1;

FIG. 15 is a rear perspective view of a second storage configuration of the barbecue grill shown in FIG. 1;

FIG. 16 is a front view of the second storage configuration of the barbecue grill shown in FIG. 15;

FIG. 17 is a rear view of the second storage configuration of the barbecue grill shown in FIG. 15;

FIG. 18 is a left side view of the second storage configuration of the barbecue grill shown in FIG. 15;

FIG. 19 is a right side view of the second storage configuration of the barbecue grill shown in FIG. 15;

FIG. 20 is a top view of the second storage configuration of the barbecue grill shown in FIG. 15; and,

FIG. 21 is a bottom view of the second storage configuration of the barbecue grill shown in FIG. 15.
